(57) **CLAIM**

The ornamental design for a sample box, as shown and described.

DESCRIPTION

FIG. 1 is a front perspective view of a sample box in a closed configuration in accordance with my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side view thereof, the left side view being a mirror image thereof;

FIG. 7 is a rear perspective view thereof;

FIG. 8 is a front perspective view thereof, in an open position of use, showing exemplary articles inserted into the sample box;

FIG. 9 is a front perspective view thereof, without articles inserted into the sample box;

FIG. 10 is a front elevation view thereof;

FIG. 11 is a rear elevation view thereof;

FIG. 12 is a top plan view thereof;

FIG. 13 is a bottom plan view thereof;

FIG. 14 is a right side view thereof, the left side view being a mirror image thereof;

FIG. 15 is a rear perspective view thereof;

FIG. 16 is a front perspective view thereof, in another open position of use, showing exemplary articles inserted into the sample box;

FIG. 17 is a front perspective view thereof, without articles inserted into the sample box;

FIG. 18 is a front elevation view thereof;

FIG. 19 is a rear elevation view thereof;

FIG. 20 is a top plan view thereof;

FIG. 21 is a bottom plan view thereof;

FIG. 22 is a right side view thereof, the left side view being a mirror image thereof; and,

FIG. 23 is a rear perspective view thereof.

(Continued)

The broken lines illustrate environmental subject matter or parts of the article. None of the broken lines form part of the claim designed.
